(57) **ABSTRACT**

A new and distinct cultivar of *Corylus* plant named 'Wepster' characterized by high vigor and an upright-spreading plant habit, yellowish-green developing and fully expanded leaves during the spring and summer, resistance to eastern filbert blight caused by the fungus *Anisogramma anomala* (Peck) E. Müller, presence of random amplified polymorphic DNA markers 152-800 and 268-580 amplified by the polymerase chain reaction and which are linked to a dominant allele for resistance to eastern filbert blight from the cultivar Gasaway, expression of incompatibility alleles S₁ and S₂ in the styles, and DNA fingerprints at 8 of 20 microsatellite marker loci differ from both parents OSU 440.005 and 'Tonda Pacifica', and from one parent at an additional 12 marker loci.

ACKNOWLEDGMENT OF GOVERNMENT
SUPPORT

This invention was made with government support under
Specific Cooperative Agreement No. 58-5358-9-447
awarded by the United States Department of Agriculture. The
government has certain rights in the invention.

2

Botanical denomination: *Corylus avellana*.
Variety designation: 'Wepster'.

BACKGROUND

The present Invention relates to a new and distinct cultivar of *Corylus* plant, botanically known as *Corylus avellana*, and hereinafter referred to by the name 'Wepster'. *Corylus avellana* is in the family Betulaceae.

The new *Corylus* resulted from a controlled cross of female parent 'Tonda Pacifica' and male parent OSU 440.005 (unpatented) made in 1997 by Shawn A. Mehlenbacher and David C. Smith. 'Tonda Pacifica' is protected by U.S. Plant Pat. No. 22,715 (issued May 8, 2012). Hybrid seeds from the cross were harvested in August 1997, stratified, and seedlings grown in the greenhouse during the summer of 1998. From this cross, a total of 182 seedling trees were planted in the field in Corvallis, Oreg., USA in October, 1998. 'Wepster' was discovered and selected by the Inventors as a single plant within the progeny of the stated cross-pollination in a controlled environment in Corvallis, Oreg. It was originally assigned the designation OSU 894.030 (unpatented), which indicates the row and tree location of the original seedling. OSU 440.005 (unpatented) is from a cross of OSU 49.073× VR 8-32 (both unpatented). OSU 49.073 is from a cross of OSU 14.084×'Tombul Ghiaghli' (both unpatented). OSU 14.084 is from a cross of 'Barcelona'×'Daviana' (both unpatented). VR 8-32 is from a cross of 'Montebello'×'Gasaway' (both unpatented). 'Tonda Gentile delle Langhe' (unpatented), the female parent of 'Tonda Pacifica', is an important cultivar in Piemonte, northern Italy. 'Barcelona', Oregon's most widely planted hazelnut cultivar, is known as 'Castanya-
era' (unpatented) where it originated in Catalunya, Spain. 'Daviana', originally from England, is the most widely planted pollinator in 'Barcelona' orchards. 'Tombul Ghiaghli', obtained from Greece, is similar to the Turkish cultivar 'Mincane' (unpatented). 'Montebello' is widely grown under several names in Sicily. 'Gasaway' is the source of a single dominant gene for resistance to eastern filbert blight.

The new cultivar was asexually reproduced by rooted suckers annually for eight years (2004-05 and 2007-12) in Corvallis, Oreg. The new cultivar was also asexually propagated by whip grafting in 2005 in Corvallis, Oreg. The unique features of this new *Corylus* are stable and reproduced true-to-type in successive generations of asexual reproduction.

SUMMARY

The following traits have been repeatedly observed and are determined to be the unique characteristics of 'Wepster'. These characteristics in combination distinguish 'Wepster' as a new and distinct cultivar:

1. High vigor and upright-spreading plant habit.
2. Yellowish-green developing and fully expanded leaves during the spring and summer.
3. Resistance to eastern filbert blight caused by the fungus *Anisogramma anomala* (Peck) E. Müller.
4. Presence of random amplified polymorphic DNA markers 152-800 and 268-580 in DNA of 'Wepster' amplified by the polymerase chain reaction. These two markers are linked to a dominant allele for resistance to eastern filbert blight from the cultivar Gasaway (unpatented).
5. Expression of incompatibility alleles S₁ and S₂ in the styles.
6. DNA fingerprints at 8 of 20 microsatellite marker loci differ from both parents, 'Tonda Pacifica' and OSU 440.005, and from one parent at an additional 12 marker loci. Additional DNA fingerprints of grandparent 'Tonda Gentile delle Langhe', standard cultivar 'Barcelona', eastern filbert blight resistance source 'Gasaway' and five cultivars released by Oregon State University hazelnut breeding program are shown in attached Table 2.

In comparisons in two replicated trials conducted in Corvallis, Oreg., plants of the new *Corylus* differed from plants of the *Corylus avellana* cultivar 'Barcelona' (unpatented), and other cultivars and selections of *Corylus avellana* known to the Inventors primarily in nut size, nut shape, kernel percentage (ratio of kernel weight to nut weight), frequency of blank nuts (nuts lacking kernels), time of pollen shed, time of nut maturity, length of the husk or involucre, and plant size. For example:

- Blank nut frequency: 'Wepster' in two trials 7.25%, 'Barcelona' in one trial 7.7%;
 Pollen shed: 'Wepster' sheds pollen about 6 days later than 'Barcelona' (average of 3 years, 2011-13);
 Nut maturity: 'Wepster' nuts mature 8 days earlier than 'Barcelona'; and
 Husk Length: 'Wepster' 2 times nut length, 'Barcelona' 1.5 times nut length.

BRIEF DESCRIPTION OF THE DRAWINGS

The accompanying colored photographs illustrate the overall appearance of the new cultivar, showing the colors as true as it is reasonably possible to obtain in colored reproductions of this type. Colors in the photographs may differ slightly from the color values cited in the detailed botanical description which accurately describe the colors of the new *Corylus*.

FIG. 1 shows typical nuts, raw kernels, and blanched kernels of 'Wepster' hazelnut (OSU 894.030) compared to those of 'Yamhill' hazelnut.

FIG. 2 shows the typical nuts, raw kernels, and blanched kernels of 'Wepster' hazelnut (OSU 894.030) compared to those of 'Barcelona', 'Felix', and 'York' hazelnut cultivars.

FIG. 3 shows the blanched kernels of 'Wepster' hazelnut (OSU 894.030).

FIG. 4 shows the tree of the new cultivar 'Wepster' growing in a field in January, in Corvallis, Oreg.

FIG. 5 shows a pruned tree of the new cultivar 'Wepster' in January, in Corvallis, Oreg.

FIG. 6 shows the husks and nuts of 'Wepster' hazelnut.

FIG. 7 shows a tree of the new cultivar 'Wepster,' 8th leaf, growing in a field in the summer, in Corvallis, Oreg.

DETAILED DESCRIPTION

The cultivar 'Wepster' has not been observed under all possible environmental conditions. The phenotype may vary somewhat with variations in environment such as temperature and light intensity, without, however, any variance in genotype. The aforementioned images and following observations and measurements describe plants grown in Corvallis, Oreg. under commercial practice outdoors in the field during the fall, winter and spring. Plants used for the photographs and description were propagated by tie-off layerage and growing on their own roots, and about seven years old. In the following description, color references are made to *The Royal Horticultural Society Colour Chart*, 1966 Edition, except where general terms of ordinary dictionary significance are used. The list of UPOV descriptors are from the Mar. 28, 1979 Hazelnut guidelines from UPOV.

Botanical classification: *Corylus avellana* cultivar Wepster. Parentage:

Female, or seed, parent.—*Corylus avellana* cultivar 'Tonda Pacifica' (U.S. Plant Pat. No. 22,715).

Male, or pollen, parent.—*Corylus avellana* selection OSU 440.005 (unpatented).

Propagation (type rooted suckers):

Time to initiate roots.—About 30 days at 20° C.

Time to produce a rooted young plant.—About six months at 22° C.

Root description.—Fine to thick; freely branching; 5 creamy white in color.

Propagation (type whip grafting):

Time to budbreak on the scions.—About 14 days at 25° C.

Time to produce a grafted plant.—About six months at 10 25° C.

Plant description:

Type.—Natural habit is a perennial shrub, but in commercial orchards is a single-trunk tree. Upright-spreading plant habit. 15

Growth and branching habit.—Freely branching; about 15 lateral branches develop per plant. Pinching, i.e., removal of the terminal apices, enhances branching with lateral branches potentially forming at every 20 node.

Size.—Plant height. — About 6 meters; plant diameter or spread is about 6 meters.

Vigor.—High vigor growth habit.

Lateral branch description:

Length.—About 32 cm.

Diameter.—About 6 mm.

Internode length.—About 3.0 cm.

Texture.—Smooth, glabrous.

Strength.—Strong.

Color.—Immature — 152B; mature — 152B.

Foliage description:

Arrangement.—Alternate, simple.

Length.—About 10.2 cm.

Width.—About 9.1 cm.

Shape.—Oblong to ovate.

Apex.—Obtuse to acute.

Base.—Cordate.

Margin.—Serrate.

Texture, upper and lower surfaces.—Slightly pubescent. 40

Venation pattern.—Pinnate.

Leaf bud shape.—Globular.

Time of leaf budbreak.—Descriptor=6 (medium to late).

Coloration of leaf bud.—178C.

Time of leaf fall.—Descriptor=4 (between 'Tonda Gentile delle Langhe' and 'Barcelona').

Color.—Developing foliage, upper surface 144A, lower surfaces: 187A. Fully expanded foliage, upper surface: Spring and summer, 143A; late summer and fall, 143A. Fully expanded foliage, lower surface: Spring and summer, 139C; late summer and fall, 139C. Venation, upper surface: Spring and summer, 139C; late summer and fall, 139C. Venation, lower surface: Spring and summer, 139D; late summer and fall, 139D. 55

Petiole description:

Length.—About 2.7 cm.

Diameter.—About 1.8 mm.

Texture, upper and lower surfaces.—Pubescent.

Color.—Upper surface: Spring and summer, 139D; late summer and fall, 139D. Lower surface: Spring and summer, 139D; late summer and fall, 139D.

Flower description:

Male inflorescences.—Catkins, color prior to elongation 65 176C.

Female inflorescence.—Style color 048B to 047B.

Time of pollen shed.—Descriptor=6 (same as 'Daviana', 'Cosford', and 'Tonda Romana').

Catkin length.—29.5 mm, descriptor=5 (medium).

Time of female flowering.—Descriptor=5 (medium).

Time of female flowering compared to male flowering.—Protogyny, descriptor=1 (earlier).

Involucr constriction.—Absent.

Involucr length.—Twice length of nut, descriptor=7.

Size of indentation.—Descriptor=7 (strong).

Strength of serration of indentation.—Descriptor=7 (strong).

Pubescence on husk.—Descriptor=9 (present).

Thickness of callus at base.—Descriptor=5 (medium).

Jointing of bracts.—Descriptor=2 (on one side).

Nut description:

Length.—About 18.3 mm.

Width.—About 19.0 mm.

Depth.—About 16.6 mm.

Nut shape.—Round.

Nut shape index $[(width+depth)/2*length] - 0.97$.

Nut compression index $(width/depth)$.—1.15.

Nut shell color.—164A.

Nut weight.—About 2.39 grams.

Kernel weight.—About 1.11 grams.

Kernel percentage (kernel weight/nut weight).—About 43.9%.

Number of fruits per cluster.—Two to three.

Number of stripes on shell.—Descriptor=5 (medium).

Prominence of fruit apex.—Slight, descriptor=3.

Size of fruit pistil.—Very small, descriptor=3.

Hairiness of top of fruit.—Weak, descriptor=3.

Curvature of nut basal scar.—Flat.

Double kernels.—Absent.

Kernel shape.—Globular.

Shape of kernel in cross-section.—Circular.

Lateral groove in kernel.—Absent.

Corkiness of pellicle of kernel.—Descriptor=5 (medium corky).

Nut yield (pounds per tree or per acre).—Total 25.91 kg per tree, years 3 to 7 (1st trial) (very high) total 19.67 kg per tree, years 3 to 7 (2nd trial).

Storability of fruits.—Excellent, similar to OSU releases and check cultivars.

45 Disease/pest resistance: Plants of the new *Corylus* are highly resistant to eastern filbert blight caused by the fungus *Anisogramma anomala* (Peck) E. Müller. Plants of the new *Corylus* are highly resistant to bud mites (*Phytoptus avel-lanae* Nal.), while plants of 'Tonda Gentile delle Langhe' are highly susceptible, and plants of 'Barcelona' are highly resistant.

Temperature tolerance: Plants of the new *Corylus* have been observed to tolerate temperatures from -10 to 38 degrees C. in the field in Corvallis, Oreg.
